COMBINED TABLE LAMP BASE AND DECANTER

Morris G. Levy, Jr., 1470 W. Minnehaha Parkway,
Minneapolis, Minn. 55427

Filed Mar. 14, 1969, Ser. No. 16,246

Term of patent 14 years

Int. Cl. D26—02

U.S. Cl. D48—20

FIG. 1

FIG. 2

FIG. 3

FIG. 1 is a front elevational view of a combined table lamp base and decanter embodying my design;
FIG. 2 is a side elevational view thereof;

FIG. 3 is a rear elevational view thereof;

FIG. 4 is a top plan view thereof; and

FIG. 5 is a bottom plan view thereof.

A side elevational view of the side opposite that shown in FIG. 2 is substantially a mirror image thereof.

I claim:

The ornamental design for a combined table lamp base and decanter, as shown and described.
